UNITED STATES PATENT OFFICE.

GEORGE ALFRED DENNY, OF LONDON, ENGLAND.

ORE-GRINDING MACHINE.

No. 909,286.

Specification of Letters Patent.

Patented Jan. 12, 1909.

Application filed June 18, 1907. Serial No. 379,633.

To all whom it may concern:

Be it known that I, GEORGE ALFRED DENNY, a subject of the King of Great Britain and Ireland, and resident of Salisbury 5 House, London Wall, London, in the county of London, England, have invented certain new and useful Improvements in Ore-Grinding Machines, of which the following is a specification.

10 This invention relates to grinding machines, and has specially in view certain improvements in the type of grinding machines known as "cone and shell" machines in which provision is made for utilizing the 15 centrifugal force of the machine to assist in feeding the material, thereby dispensing, to a large extent, with the use of water.

With the above and many other objects in view, the invention contemplates certain 20 novel features of construction and combination of parts which will be described in detail in the following description, pointed out in the claim, and illustrated in the drawings.

In said drawings, wherein a preferred embodiment of the invention has been shown,—Figure 1 is a side elevation of the machine showing its connection with the source of power and also the manner of feeding material to the grinding members. Fig. 2 is a 30 top plan view of the same. Fig. 3 is a part sectional view of the structure shown in Fig. 1. Fig. 4 is a detail view of the connection between the grinding cone and its operating shaft. Fig. 5 is a detail view of the operating shaft showing its connection with the guiding sleeve.

Like characters of reference refer to corresponding parts.

In the accompanying drawings, 10 designates a suitable base which has mounted thereon a frame composed of side members 11—11 and a top connecting horizontal member 12 provided with a central opening 13. Said frame, which will be hereinafter referred 40 to as the lower frame, forms a base support for an upper frame which is of similar construction as the lower frame, but of a smaller size, and comprises the two side members 14—14 and top connecting horizontal member 15 provided with a central opening 16 in alinement with the opening 13 in the lower frame.

The grinding mechanism of the machine is composed of two hollowed inverted cone 55 shaped members 17 and 18, respectively. The cone-shaped grinding member 18 is

mounted on the base 10 and has an inlet formed in its lower extremity or apex, as at 19 which is in communication with a feeding pipe 21 which conveys the material to the 60 said member 18. The members 17 and 18 are of such a size as to permit of one being freely revolved within the other, and as shown in the preferred construction, the member 18 is a stationary one, it being held 65 in rigid engagement with the base 10 by means of the ribs 22. Each of said members is provided with grinding teeth 23—24, respectively which are held on the surfaces of the members by means of bolts or the like 70 25, in such a manner as to permit of their being readily removed when desired or necessary.

A vertically arranged drive or operating shaft 26 has a keyed connection 27 with a 75 guiding sleeve 28, and said shaft, with its connected sleeve extends through the opening in each of the upper and lower frames, suitable bearings 29—30 being interposed between the sleeve and the sides of the 80 openings to reduce friction. The keyed connection between the shaft and its guiding sleeve is arranged longitudinally and is of a loose nature which permits of the shaft being adjusted vertically with reference to said 85 guiding sleeve, but a relative rotary movement of the two members will be prevented.

The lower portion of shaft 26 projects beyond the top member of the lower frame and at its extreme lower end a rectangular frame 90 31 has two of its diametrically opposite sides pivotally connected thereto. A supporting truss or beam 32 incloses said rectangular frame 31, and is arranged to engage and be pivotally connected with the side members 95 of said frame that are not connected with the end of the shaft. The outer ends of said beam or truss are connected with the head of the grinding cone 17. The form of connection between the truss or beam and the end 100 of the shaft forms what is known as a "gimbal" joint, and provided for a universal movement of the grinding cone 17 to compensate for wear etc. upon the grinding surface thereof.

The portion of the guiding sleeve 28 within the upper frame has fast thereon a horizontally arranged beveled gear wheel 33 with which meshes a vertically arranged bevel pinion 34 carried by a horizontal shaft 35 110 which projects through and has bearing within one of the side members of the upper

frame, the outer end of said shaft carrying pulleys 36—37, which may be connected with a suitable source of power.

The upper end of the vertical shaft has a 5 hollow threaded portion 38 adapted to receive a similarly threaded adjusting rod 39 carrying a hand wheel 40, the hub 41 of which normally rests upon a cap 42 at the upper end of the guiding sleeve. As shown 10 more clearly in Fig. 3 of the drawings, the upper end of the guiding sleeve projects beyond the upper plane of the end of the shaft thereby providing a clearance space for the longitudinal adjustment of the shaft when 15 the hand wheel 40 is operated to effect such adjustments.

The operation of the machine is as follows:—The material to be acted upon enters through the inlet of the stationary cone 20 where it is caught and crushed between the spirally arranged teeth of the rapidly revolving cone and the teeth of the stationary cone. And in the crushing operation, the tendency of the spiral teeth assisted by the 25 centrifugal force exerted by the revolving cone, causes the material to be carried upwardly during the crushing operation until it reaches the top of the stationary cone where it flows out into a suitable delivery 30 chute 43 at one side of the said stationary cone.

In grinding or crushing various grades of ores, it is necessary that different degrees of crushing be had for certain grades of ores. 35 To allow for this, the described method of adjusting the drive shaft with its connected rotary grinding cone is provided, by means of which the said rotary cone may be quickly 40 adjusted in a vertical plane relatively to the stationary grinding cone. And it will be understood that by means of the gimbal connection between said rotary grinding member and the drive shaft, any inequalities in the material being treated, or any wear on 45 the teeth of either of the grinding cones, will cause said rotary cone to automatically assume a position to compensate therefor,

without in any way interfering with its proper grinding of the material.

A prominent and distinctive feature of the 50 invention resides in the underfeed arrangement for the material to be crushed, by means of which said material is conveyed to the lower portion of the stationary crushing cone and from that point caused to ascend until the top of said cone is reached where it is delivered in a finely crushed or powdered condition. By this arrangement 55 it is possible to use the machine with little or no water pressure, other than what is necessary to cause the material to flow to the point of entry into the stationary cone.

While in the foregoing description I have set forth the preferred form of the invention and also the preferred manner of using the 65 same, I wish it to be understood that I do not limit myself to the precise construction and method of use therein set forth, as changes in the construction and manner of use may be resorted to without departing 70 from the spirit of the invention.

I claim as my invention:—

A grinding machine comprising a lower stationary cone member having at its apex a bottom inlet and provided upon its inner 75 inclined face with a plurality of longitudinally arranged grinding teeth, a vertically disposed drive shaft arranged above and concentric to said stationary cone member, means for adjusting said shaft vertically, 80 means for rotating said shaft, an upper rotary cone member nested within the lower cone member and provided on its outer inclined face with a plurality of longitudinally arranged grinding teeth, and a gimbal joint 85 connection suspending the rotary cone member at the top from the lower end of the drive shaft.

In witness whereof I have affixed my signature in presence of two witnesses.

GEORGE ALFRED DENNY.
